UNITED STATES PATENT OFFICE.

HENRY H. SESSIONS, OF CHICAGO, ILLINOIS.

CAR CONSTRUCTION.

SPECIFICATION forming part of Letters Patent No. 634,218, dated October 3, 1899.

Application filed February 25, 1899. Serial No. 706,822. (No model.)

To all whom it may concern:

Be it known that I, HENRY H. SESSIONS, a citizen of the United States, residing at Chicago, in the county of Cook and State of Illinois, have invented a new and useful Improvement in Car Construction, of which the following is a specification.

My invention relates particularly to an improvement in buffing equipment for blind-end cars.

My primary object is to provide such a construction and arrangement of the buffing-mechanism parts as to avoid the dangerous weakening of the buffer-beam inherent in constructions now in common use; and a further object is to provide certain improvements in the details of construction of the buffer-plate and its manner of attachment to the side buffer-stems.

In the accompanying drawings, Figure 1 is a broken plan section of one end of the lower frame of a car-body equipped with my improvements, the section being taken as indicated at line 1 of Fig. 3; Fig. 2, a similar plan section taken at line 2 of Fig. 3; Fig. 3, a central vertical longitudinal section taken on line 3 of Fig. 1; Fig. 4, a broken view, in front elevation, of the buffer-beam and attendant parts; and Figs. 5, 6, and 7 details 30 of the means for connecting the side buffer-stems to the movable buffer-plate.

In cars of the character herein described, the platform being dispensed with, the buffer-beam or platform end sill is set back close against the end sill of the car. Heretofore it has been the common practice to arrange the heavy central buffer-spring in a recess in the buffer-beam, thereby greatly weakening said beam, besides throwing practically the whole 40 shock of collision upon the end sill of the car.

In my improved construction the central buffer-stem extends completely through the end sill of the car, (as well as through the buffer-beam,) and the heavy central buffer-spring is located between the rear end of said central stem and a short cross-beam, joining the two center sills of the car a short distance back of the end sill.

A A' represent the two center sills of the car-body; B B', the two intermediate sills thereof; C, the end sill; D, the buffer-beam corresponding to the platform end sill where

a platform is present; E, the dead-block, provided with a metallic facing E'; F, the spring-held buffer-plate or buffer-head; F', the center buffer-stem, and F² F³ the side buffer-stems.

The parts C, D, E, and E' are firmly secured together by bolts a, the central ones of which serve also to attach a metallic facing or angle b to the rear face of the sill C. Directly beneath the center sills A A' and firmly secured thereto by bolts c are the main or draft-steel I-beams G G' now well known. Framed in between the two center sills A A' and further secured to said sills by bolts d is a short transversely-extending beam H, supplied on its front side with a metallic facing H', secured by bolts d', and on its lower side with a metallic plate H², secured by bolts d². The facing H' is provided with a cup-like boss H³, which serves to receive the rear end of the center buffer-spring I. It is further provided with a rearwardly-projecting flange, which embraces the front margin of the bottom plate H².

The end sill, buffer-beam, and dead-block are provided with perforations within and through which the buffer-stems move. The center buffer-stem is provided with a reduced end, which projects back of the plate b and receives a movable cup-like casting or forging J, which in turn receives the front end of the buffer-spring I. The part J is engaged by the annular shoulder of the stem and moved away from the plate b when sufficient force is exerted at the buffer-plate, the plate b serving to limit the return movement.

The side buffer-stems are equipped toward their rear ends with springs K, confined between shoulders f on the stems, and double angles secured each at its wings to a center sill and an intermediate sill in a well-understood manner. The stems project through the irons K' and are supplied with removable collars f', between which and the irons K' are confined auxiliary springs K², which serve to cushion the return movement of the stems.

The novel manner of attachment of the side buffer-stems to the buffer-plate is illustrated in Fig. 2 and Figs. 5 to 7, inclusive. Each stem F² F³ is provided at its front end with a vertical head or swivel g, forming, with the stem, a T. The stem is pivotally secured to

the buffer-plate by means of a perforated plate L, having channels h on its inner side, above and below the perforation, adapted to receive the vertical head g. These channels 5 are preferably formed by "striking up" the metal of the plate above and below the perforation, thereby forming raised portions h'. The plate is supplied with perforations h² for the insertion of rivets. The parts are put together 10 by slipping the buffer-stem through the opening of the attaching-plate till the head g engages the bearing or depression at h, the collar f' being attached after the buffer-plate is in place on the car. The center stem 15 is preferably left unattached to the buffer-plate.

The novel construction of the buffer-plate F is shown in Figs. 2 and 3. It comprises an angle-iron of the length shown in Fig. 2, the 20 rearwardly-turned horizontal wing k of which supports the tread l and the vertical downwardly-turned wing k' of which has secured to it, as by rivets k², a removable chafing-plate k³. The chafing-plate protects the main part 25 of the buffer-plate, and when worn out may be replaced, thus economizing in the matter of repairs. The horizontal portion of the angle affords a firm foundation for the tread l and, moreover, acts as a strengthening-rib to 30 the vertical part k'.

The buffer-beam is provided with a forward-projecting tread or foot-board m, which rests loosely at its forward margin upon the board l.

35 Figs. 1 and 3 show the buffer-beam sustaining fragments of the hood-supporting uprights N. A fragment of the front yoke or diaphragm face-plate P of the vestibule extension is shown attached to the buffer-plate. 40 In Figs. 3 and 4 a draw-bar guide Q is shown depending from the draft-beams G G'.

Fig. 2 shows the side buffer-stem F³ confined closely in the perforation through which it moves, while at the inner side of the stem 45 F² is provided a space p to permit the stem F² to swing inwardly when the buffer-plate departs from a right angle. In this construction the stem F³ acts as a close-fitting guide, which prevents lateral movement of the buffer-plate. Heretofore it has been the practice to provide for the change in angle of the 50 buffer-plate by allowing "play" at both side stems, thus permitting a lateral movement of the buffer-plate with a consequent rattling and wearing action. This difficulty is entirely obviated by the new construction, which is considered as highly important.

From the foregoing description it will be readily understood that the shock sustained 60 by the center buffer-stem F' is transmitted freely to the casting J and spring I, (shown double,) where it is dissipated or transmitted gradually to the car-frame through the block H. The block H, being short, may be made of 65 such thickness as to withstand any reasonable shock without increasing the weight or cost of construction to such an extent as would be

necessary were the end sill C to be enlarged to obviate the dangers of the old construction. Furthermore, the enlargement of the end sill 70 is impracticable for other reasons readily appreciated by car builders.

I do not confine myself to the exact details of construction shown, so far as the feature of extending the center buffer-stem back of the end sill is concerned, as this feature of my invention will be found present in any construction wherein is employed a main or center buffer-spring attached to the framework of the car in the rear of the end sill and 75 connected at its free end with the rear end of a buffer-stem, the front end of which engages the movable buffer-plate. In other words, the spring is so located in the improved construction as to avoid weakening the buffer-beam, and preferably, also, the end sill, in any degree. Preferably, also, the spring is attached to the frame by means distinct from and independent of the end sill and buffer-beam, as shown. Of course the buffer-beam 80 and end sill may be made integral without departure from my invention.

What I claim as new, and desire to secure by Letters Patent, is—

1. In a car, the combination with the longitudinally-extending sills and an end sill of a car-body, of a suitably-supported movable buffer-plate, a center buffer-stem engaging the buffer-plate at its front end, a main or center buffer-spring located back of said end sill, means for attaching said spring to the framework of the car-body, and means on the rear end of said buffer-stem for engaging said spring, substantially as and for the purpose set forth. 95

2. In a car, the combination with the longitudinally-extending sills and an end sill of the car-body, of a suitably-supported movable buffer-plate, a center buffer-stem extending back of said end sill, a center or main buffer-spring at the rear end of said stem, and means for attaching said spring to said longitudinally-extending sills independently of the end sill, substantially as and for the purpose set forth. 100

3. In a car, the combination with the two longitudinally-extending center sills and an end sill of the framework, of a suitably-supported buffer-plate, a center buffer-stem extending through said end sill, a main buffer-spring connected to the rear end of said stem, and a transversely-extending block or the like attached to said center sills and connected with the rear end of said spring, substantially as and for the purpose set forth. 115

4. In a car, the combination with the longitudinally-extending sills, end sill, and buffer-beam, of a movable buffer-plate, spring-held side stems attached thereto, a center buffer-stem extending from the buffer-plate through 120 buffer-beam and end sill, and equipped at its rear end with a spring-engaging head, a center buffer-spring back of said end sill held at one end by said head, and a transversely-ex- 125

tending block supported by said sills and provided on its front face with a metallic spring-engaging plate which supports the rear end of said spring, substantially as and for the purpose set forth.

5. In a car, the combination with the framework, of buffing mechanism, comprising a buffer-plate, spring-held side buffer-stems supporting said plate at its ends, said stems having heads or swivels forming with the stems T's, and attaching-plates secured to the buffer-plate provided with openings for the buffer-stems and on their sides adjacent to the buffer-plate and above and below said

15 openings with vertically-extending channels affording bearings for said heads or swivels, substantially as and for the purpose set forth.

6. In a car, the combination with the longitudinally-extending sills and buffer-beam, of a buffer-plate, a buffer-stem pivotally attached to the plate near one end moving in a close-fitting perforation through said buffer-beam, and a second buffer-stem pivotally secured to said buffer-plate toward its opposite end, and moving in a perforation through 25 said buffer-beam which is enlarged to permit inward swinging of said last-named stem when the buffer-plate departs from a right angle, substantially as and for the purpose set forth.

HENRY H. SESSIONS.

In presence of—

R. T. SPENCER,
D. W. LEE.
